(57) **CLAIM**

The ornamental design for a wall-mounting type television, as shown and described.

DESCRIPTION

FIG. 1 is a front elevational view of a wall-mounting type television showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front and left side perspective view thereof;

FIG. 8 is a front and left side perspective view showing the wall-mounting type television linked with a control module in a use state; and,

FIG. 9 is an enlarged view of portion 9 in FIG. 7.

The broken lines in the drawings illustrate portions of the wall-mounting type television which form no part of the claimed design.

The broken lines in FIG. 8 depicting the control module either form no part of the claimed design.

The oblique shade lines in the drawings represent a reflective surface.
